LEVIS PASSMORE, OF PHILADELPHIA, PENNSYLVANIA, ASSIGNOR
TO W. W. STEEL, OF SAME PLACE.

Design No. 3,355, dated January 26, 1869.

DESIGN FOR A GATE.

The Schedule referred to in these Letters Patent and making part of the same.

To all whom it may concern:

Be it known that I, LEVIS PASSMORE, of the city and county of Philadelphia, State of Pennsylvania, have originated a new Design for a Gate; and I do hereby declare that the accompanying drawing, and following explanation thereof, form a full, clear, and exact description of the said design.

In the drawing, the figure represents a front view of the gate, which is edged with a denticulated rib, *a*, the space between which and a panel, formed by another denticulated rib, is ornamented as shown in the drawing.

Within this panel is a protuberant or convex oval figure of lattice-work, formed by cross-strips, and hav-

ing a central ornament, all as clearly illustrated in the drawing.

The corner spaces, left between the panel, with denticulated edging-rib and the oval figure, have the foliated ornaments shown.

I claim the design for a gate, substantially as described, and illustrated in and by the accompanying drawing.

In testimony whereof, I have signed my name to this specification, in the presence of two subscribing witnesses.

Witnesses:

E. H. BAILEY,
C. B. PRICE.

LEVIS PASSMORE.
